(57) **CLAIM**

The ornamental design for a commercial lifting device-jack stand, as shown and described.

DESCRIPTION

FIG. 1 is a top plan view of a commercial lifting device-jack stand of the present invention;

FIG. 2 is a bottom view;

FIG. 3 is a right side elevational view;

FIG. 4 is a left side elevational view;

FIG. 5 is a front elevational view; and,

FIG. 6 is a rear elevational view of the present invention.

The portion in the above FIGS. shown in broken lines form no part of the ornamental design of the present invention. The dash dotted lines which define the bounds of the claimed design in FIGS. 5 and 6 form no part thereof.
